UNITED STATES PATENT OFFICE.

PERCY R. THORNE AND RAYMOND D. WELTON, OF VINCENNES, INDIANA.

DISK JOINTER FOR PLOWS.

No. 809,477.

Specification of Letters Patent.

Patented Jan. 9, 1906.

Application filed May 25, 1905. Serial No. 262,263.

To all whom it may concern:

Be it known that we, PERCY R. THORNE and RAYMOND D. WELTON, citizens of the United States, residing at Vincennes, in the county of Knox and State of Indiana, have invented certain new and useful Improvements in Disk Jointers for Plows; and we do declare the following to be a full, clear, and exact description of the invention, such as will enable others skilled in the art to which it appertains to make and use the same.

This invention relates to improvements in jointers for plows.

The object of the invention is to provide a jointer for plows which will efficiently cut its way through all kinds of weeds and trash, thereby preventing the same from clogging the plow.

A further object is to provide means for attaching the jointer to the plow-beam to permit said jointer to be adjusted laterally, means being also provided for raising and lowering the jointer.

With these and other objects in view the invention consists of certain novel features of construction, combination, and arrangement of parts, as will be hereinafter described and claimed.

In the accompanying drawings, Figure 1 is a side view of a portion of a plow-beam, showing the jointer applied thereto. Fig. 2 is a front elevation of the same, partly in section. Fig. 3 is a vertical cross-sectional view through the beam and the rear end of the upper attaching-plate, showing the clamping device for securing the rear end of the same to the beam. Fig. 4 is a top plan view of the upper attaching-plate. Fig. 5 is a similar view of the lower attaching-plate. Fig. 6 is a vertical sectional view through the jointer and its attaching-bracket, and Fig. 7 is a similar view taken at right angles to Fig. 6.

Referring more particularly to the drawings, 1 denotes the plow-beam, on the under side of which is secured an upper attaching-plate 2. Said plate is provided near its forward end with slots 3, said slots being arranged on opposite sides of the center of the plate, as shown. Through the slots 3 are inserted upwardly-projecting bolts 4, which are adapted to project on each side of the plow-beam, the upper ends of the bolts passing through a clamping-bar 5, which engages the upper side of the plow-beam. On the upper ends of the bolts 4 are adapted to be screwed nuts 6, whereby the front end of the attach-

ing-plate 2 is firmly clamped to the plow-beam. The rear end of the plate 2 is recessed or cut away, as at 7, and in said cut-away or recessed portion is slidably mounted a pair of 60 clamping-bars 8, said bars being provided with alined longitudinally-disposed slots, through which is passed a securing-bolt 7', which also passes through an aperture 8' in the end of the plate 2. The outer ends of the 65 clamping-bars 9 are provided with upwardly-projecting lugs 10, which are roughened on their inner sides and are adapted to engage the opposite sides of the plow-beam. When the lugs 10 have been firmly engaged with 70 the sides of the plow-beam, the nut on the bolt 9 is tightened, thereby holding said clamping-bars into tight engagement with the beam, and thus securing the rear end of the plate 2 to the beam. The front end of the plate 2 is 75 provided with a downwardly-projecting right-angularly-formed extension 13, in which is formed a transverse horizontally-disposed slot 14.

On the lower side of the plate 2 is secured 80 a lower attaching-plate 15, said plate being provided near its rear end with a transversely-disposed slot 16, through which and a centrally-disposed aperture 17, formed in the plate 2, is inserted a bolt 18. On the lower 85 end of the bolt 18 is screwed a nut 19, thereby adjustably securing this end of the plate 15 to the upper attaching-plate 2. On the forward end of the lower plate 15 is formed a downwardly-projecting right-angularly-disposed projection 20, in which is formed a centrally-disposed aperture 21. Through this aperture 21 and through the slot 14 in the extension 13 of the upper plate is passed a bolt 22, on the outer end of which is screwed a 95 nut, whereby the forward end of the lower plate is adjustably secured to the upper plate. On the under side of the plate 15 is formed a downwardly-projecting obliquely-disposed arm 23, in one side of which is formed a longitudinally-disposed channel 24. The arm 23 is also provided with a longitudinally-disposed slot 25. In the channel 24 of the arm 23 is adjustably secured the upper end of a jointer-standard 26, said standard being provided near its upper end with a bolt-hole, through which and the slot 25 of the arm 23 is arranged a bolt 27. Said bolt is provided on its end with a nut 28, which when screwed up into engagement with the side of the arm 100 23 will securely hold the standard 26 in any of its adjusted positions on the arm 23, thus

permitting the jointer to be raised or lowered, as desired. On the lower end of the standard 26 is formed an enlargement 28, said enlargement being provided with a vertically-disposed aperture 29, the lower side of the enlargement 28 being provided with a roughened or serrated surface.

Adapted to be engaged with and secured to the enlargement 28 of the standard 26 is a bearing-bracket 30, said bracket being provided with a right-angularly formed arm, the upper side of which is provided with a roughened surface which is adapted to engage the roughened surface of the enlargement 28. The right-angularly-formed arm of the bracket 30 is also provided with a vertically-disposed aperture 31, which is adapted to align with the aperture 29 in the enlargement 28, and through said aligned apertures is passed a securing-bolt 32, on the lower end of which is adapted to be screwed a nut 33, which when screwed upon the bolt 32 will securely clamp the bracket 30 to the enlargement 28. In the vertical arm of the bracket 30 is formed a transversely-disposed aperture 33', in which is adapted to be inserted a bearing-box 34. In the box 34 is mounted a short shaft or spindle 35, between which and the box 34 is disposed a bushing 36. On the shaft or spindle 35, adjacent to the outer end of the same, is rigidly secured a circular plate 37, to which is bolted or otherwise secured a disk jointer 38. Said disk is provided with a centrally-disposed aperture 39 to fit over the end of the shaft or spindle, the outer end of said shaft or spindle being provided with screw-threads, on which is adapted to be screwed a nut 40, by which the disk jointer is rigidly held on the spindle 35. The disk jointer is here shown as secured to the plate 37 by means of screw-bolts 41, which are countersunk in the disk 38. On the opposite end of the spindle 35 is screwed a securing-nut 42, whereby the shaft or spindle 35 is secured in the bracket. The box 34 is secured in the aperture 33 of the bearing-bracket by means of a set-screw 43.

A jointer constructed and arranged as herein shown and described may be adjusted laterally on the plow-beam and may be also lengthened or shortened, the construction of the parts also being such as to permit the jointer to be arranged on either side of the standard, as will be understood.

While the device is shown as being connected with a wooden-beam plow, it is obvious that the same may be connected or applied to a steel or iron beam without materially changing the construction of any of the parts.

From the foregoing description, taken in connection with the accompanying drawings, the construction and operation of the invention will be readily understood without requiring a more extended explanation.

Various changes in the form, proportion, and the minor details of construction may be

resorted to without departing from the principle or sacrificing any of the advantages of this invention.

Having thus described our invention, what we claim as new, and desire to secure by Letters Patent, is—

1. A jointer of the character described comprising upper and lower attaching-plates, means for clamping said upper plate to the plow-beam, means whereby said plates are connected together to permit them to be adjusted laterally, a depending arm arranged on said lower plate, a jointer-standard adjustably secured to said arm, and a disk jointer detachably connected to the lower end of said standard, substantially as described.

2. A jointer of the character described comprising an upper attaching-plate, adjustable clamping-bolts to secure the forward end of said plate to the plow-beam, adjustable clamping-bars to secure the rear end of said plate to the beam, a downwardly-projecting right-angularly-disposed, horizontally-slotted extension formed on the forward edge of said upper plate, a transversely-slotted lower attaching-plate adjustably connected to said upper plate, a depending obliquely-disposed arm formed integrally with said lower attaching-plate, said arm having formed therein a longitudinally-disposed channel and a longitudinally-disposed slot, a jointer-standard adjustably mounted in said channel, a bolt adapted to pass through said standard and through the slot in said arm to adjustably secure said standard to said arm, and a disk jointer adapted to be secured to the lower end of said standard, substantially as described.

3. A jointer of the character described comprising upper and lower attaching-plates, means for clamping said upper plate to the plow-beam, means whereby said plates are connected together to permit them to be adjusted laterally, a depending arm arranged on said lower plate, a jointer-standard adjustably secured to said arm, an apertured enlargement formed on the lower end of said standard, a right-angularly-formed bearing-bracket secured to said enlargement, a jointer-shaft arranged in said bracket, and a disk jointer secured on said shaft, substantially as described.

4. A jointer of the character described comprising upper and lower attaching-plates, means for clamping said upper plate to the plow-beam, means whereby said plates are connected together to permit them to be adjusted laterally, a depending arm arranged on said lower plate, a jointer-standard adjustably secured to said arm, an apertured enlargement formed on the lower end of said standard, said enlargement having a roughened lower surface, a right-angularly-formed bearing-bracket, having a roughened upper surface to engage the roughened surface of

said enlargement, an attaching-bolt adapted to be passed through the aperture in said enlargement and an alined aperture in said bracket, a horizontally-disposed bearing-box 5 arranged in said bracket, a jointer-shaft mounted in said box, a bushing arranged between said shaft and said boxing, a plate secured to said shaft, near one end of the same, a nut adapted to be screwed on the other end 10 of the shaft, a disk jointer arranged on the end of said shaft adjacent to said plate, bolts to secure said disk to said plate, and a nut

adapted to be screwed on the end of said shaft against the outer face of said disk, substantially as described.
